(57) **ABSTRACT**

The present disclosure relates to a display apparatus and a method for monitoring the same. A display apparatus is provided. The display apparatus comprises a display unit, a backlight module, a light sensor, and a controller. The backlight module is located on a first side of the display unit. The light sensor is located on a second side of the display unit different from the first side. The light sensor faces away from the display unit for detecting light comprising ambient light and reflected light from the display unit and generates a first brightness value. The controller determines the display apparatus malfunction based on the first brightness value.

FIG. 6

DISPLAY APPARATUS AND METHOD FOR MONITORING THE SAME

BACKGROUND

1. Field of the Disclosure

The present disclosure relates to a display apparatus and a method for operating the same. More particularly, the present disclosure relates to a display apparatus and a method for monitoring whether the display apparatus functions properly.

2. Description of the Related Art

As display apparatuses are widely used in different environments, how to ensure the reliability and robustness of display apparatuses under harsh conditions has become an important issue. For example, if a display apparatus is placed outdoors, the display apparatus may be exposed to sunlight, wind, and rain. The outdoor operating conditions may cause problems such as deterioration of the backlight module or display unit and accidental shut-down of components of the display apparatus.

In view of the above, there is a need to provide a display apparatus with a self-detection capability, so as to ensure that the display apparatus is functioning properly. There is also a need for the administrator or owner of the display apparatus or an advertiser to monitor whether the display apparatus is functioning properly.

SUMMARY

In one aspect according to some embodiments, a display apparatus comprises a display unit, a backlight module, a light sensor, and a controller. The backlight module is located on a first side of the display unit. The light sensor is located on a second side of the display unit different from the first side. The light sensor faces away from the display unit for detecting light comprising ambient light and reflected light from the display unit and generates a first brightness value. The controller determines the display apparatus malfunction based on the first brightness value.

In a preferred embodiment, the controller further controls the backlight module based on the first brightness value.

In one aspect according to some embodiments, a method for monitoring a display apparatus comprises detecting light comprising ambient light and reflected light from the display apparatus; generating a first brightness value based on the detected light; and determining a display apparatus malfunction based on the first brightness value.

In a preferred embodiment, the method further comprises controlling the backlight of the display apparatus based on the first brightness value.

Other aspects and embodiments of the present disclosure are also contemplated. The foregoing summary and the following detailed description are not meant to limit the present disclosure to any particular embodiment but are merely meant to describe some embodiments of the present disclosure.

BRIEF DESCRIPTION OF THE DRAWINGS

For a better understanding of the nature and objects of some embodiments of the present disclosure, reference should be made to the following detailed description taken in conjunction with the accompanying drawings. In the

drawings, identical or functionally identical elements are given the same reference numbers unless otherwise specified.

FIG. 1 illustrates a display apparatus according to some embodiments of the present disclosure.

FIG. 2 illustrates a display apparatus and a transparent plate according to some embodiments of the present disclosure.

FIG. 3 is a flow chart for monitoring a display apparatus according to some embodiments of the present disclosure.

FIG. 4 is a flow chart for monitoring a display apparatus according to some embodiments of the present disclosure.

FIG. 5A is a flow chart for monitoring a display apparatus according to some embodiments of the present disclosure.

FIG. 5B illustrates a frame according to some embodiments of the present disclosure.

FIG. 6 is a flow chart for monitoring a display apparatus according to some embodiments of the present disclosure.

DETAILED DESCRIPTION

FIG. 1 illustrates a display apparatus 1 according to some embodiments of the present disclosure. As shown in FIG. 1, the display apparatus 1 includes a protective plate 11, a display unit 12, a backlight module 13, a sensing device 14, a controller 15, and a communication module 16. The display unit 12 includes a display area 121 and a non-display area 122. The display area 121 may be surrounded by the non-display area 122. The communication module 16 may communicate with any external apparatus through a wired connection and/or a wireless connection. The controller 15 electrically connects to and communicates with the display unit 12, the backlight module 13, the sensing device 14, and/or the communication module 16. In some embodiments, the controller 15 may control the display unit 12, the backlight module 13, the sensing device 14, and the communication module 16.

The display unit 12 may include a liquid crystal layer. In some embodiments, the backlight module 13 may be a direct backlight module including a plurality of light sources and a backlight assembly for mounting the light sources. The light sources can be, for example, a plurality of LEDs, which may be placed on the front surface of the backlight assembly to provide backlight illumination for the display unit 12. In some embodiments, the backlight module 13 may be an edge-lit backlight module including a light source for side illumination and a light guiding plate. One or more optical films may be included in the display unit 12, the backlight module 13, or both, and can be, for example, a light diffuser, a light reflector, a brightness enhancement film, or a combination of two or more thereof. The type and the number of optical films to be used are not limited here.

In a preferred embodiment, the sensing device 14 is disposed on the display unit 12. The sensing device 14 is disposed on the non-display area 122 instead of the display area 121 of the display unit 12. Thus, the sensing device 14 would not block a portion of the display area 121. In a preferred embodiment, the sensing device 14 is disposed facing away from the display unit 12 and facing toward the protective plate 11. The protective plate 11 can be made of tempered glass or other transparent material with higher strength.

The sensing device 14 may detect or measure the magnitude of light and generate a corresponding brightness value. In some embodiments, the sensing device 14 may be a light detector or a light sensor. The sensing device 14 may detect or measure light from different sources, such as

ambient light passing through the protective plate 11 and light emitted by the backlight module 13 passing through the display unit 12 and then reflected by the protective plate 11. Thus, the brightness value generated by the sensing device 14 may present both the brightness of the environment in which the display apparatus 1 is placed and the brightness of light emitted by the display apparatus itself. Thus, the sensing device 14 can be used for detecting the ambient light and for determining whether the display apparatus functions properly. The sensing device 14 may be any device that is capable to detect or measure the magnitude of light and is not limited by the above embodiments. For example, the sensing device 14 may be an image capturing device, such as camera.

The controller 15 may control the backlight module 13 based on the brightness value generated by the sensing device 14. The controller 15 may adjust the backlight module 13 based on the brightness of ambient light. For example, if the environment is very bright, the brightness value generated by the sensing device 14 may be higher than a threshold for a time period (e.g., 10 minutes). In this case, the controller 15 may control the backlight module 13 to increase its brightness, so that the viewer can see the displayed image easily. On the other hand, if the environment is very dark, the brightness value generated by the sensing device 14 may be lower than another threshold for a time period (e.g., 10 minutes). In this case, the controller 15 may control the backlight module 13 to decrease its brightness so as to save power and avoid the glare. Additionally, the controller 15 can determine whether the display apparatus 1 functions properly and the detailed description will be provided in the paragraphs related to FIGS. 3-5.

FIG. 2 illustrates a display apparatus 1a according to some embodiments of the present disclosure. The display apparatus 1a shown in FIG. 2 is similar to the display apparatus 1 shown in FIG. 1. The components of the display apparatus 1a in FIG. 2 with the same reference numerals as those of the display apparatus 1 in FIG. 1 refer to the same or similar components, and thus their detailed descriptions are not repeated here. Different from FIG. 1, the display apparatus 1a is placed behind a transparent plate 2. The transparent plate 2 may be a glass plate of a window of a store, and thus is not a part of the display apparatus 1a. Although the display apparatus 1a is placed behind the transparent plate 2, in some embodiments, the display unit 12 may still include a protective layer (not shown) on one side of the display unit 12 opposite to the side of the display unit 12 near the backlight module 13.

In a preferred embodiment, the sensing device 14 faces toward the transparent plate 2 and faces away from the display unit 12. The sensing device 14 may be capable to detect or measure the magnitude of light and generate a corresponding brightness value. The sensing device 14 may detect or measure light from different sources, such as ambient light passing through the transparent plate 2 and light emitted by the backlight module 13 passing through the display unit 12 and then reflected by the transparent plate 2. Since the sensing device 14 may detect light reflected by the transparent plate 2 from the display unit 12 and the backlight module 13, the sensing device 14 may be used to determine whether the display apparatus functions properly. Furthermore, since the sensing device 14 may detect ambient light, the brightness value generated by the sensing device 14 can be used to adjust the backlight module 13 as mentioned above.

Please note that although the sensing device 14 is mounted on the display unit 12 in FIG. 1 and FIG. 2, it can

also be embedded in the display unit 12, attached to the periphery of the display unit 12, mounted on a housing of the display apparatus 1 (or 1a) or placed in other manners as long as it can detect light reflected by the transparent plate 2 or the protective plate 11.

In addition to sensing ambient light, the sensing device 14 in combination with the controller 15 can also be used to determine whether the display apparatus 1 (or 1a) functions properly. For example, if the backlight module 13 is broken and the display unit 12 functions properly, the brightness of the display apparatus 1 (or 1a) become very low and viewers may not be able to see the displayed content. In this situation, the sensing device 14 may detect or measure only ambient light, and the generated brightness value would remain a low and almost constant value for a long time period, such as 10 minutes. Thus, the controller 15 may determine that a display apparatus malfunction has occurred based on the generated brightness value.

FIG. 3 is a flow chart for monitoring a display apparatus 20 according to some embodiments of the present disclosure. In some embodiments, the flow chart in FIG. 3 is performed by the controller 15 of the display apparatus 1 (or 1a). During operation of the display apparatus 1 (or 1a), the sensing device 14 detects or measures the light and generates the 25 corresponding brightness values. The sensing device 14 may generate brightness values at different times. The brightness values generated by the sensing device 14 may be expressed as a function associated with time. For example, the brightness values generated by the sensing device 14 may be 30 expressed as:

$$V(t), \text{ in which } t \text{ refers to time.}$$

In operation 101, the controller 15 obtains the brightness value $V(t)$ from the sensing device 14. In operation 102, the controller 15 determines whether the brightness $V(t)$ is 35 smaller than a threshold $T1$ for a preconfigured time period. If so, the controller 15 determines the occurrence of the display apparatus malfunction (operation 103); otherwise, the controller 15 performs operation 101 again. For example, if the time period is set as 10 minutes and a 40 brightness value is obtained every second, then the controller 15 may determine that the brightness of the display apparatus 1 (or 1a) is too low if 600 continuous brightness values are lower than the threshold $T1$. In some embodiments, the determination of operation 102 may be expressed as:

$V(t) < T1$ for every t in the range from $(t1-m+1)$ to $t1$, in which $t1$ denotes the current time and m is an integer and is determined based on the preconfigured time period and the rate of obtaining brightness values.

Otherwise, the controller 15 determines that the display apparatus 1 (or 1a) functions properly and performs operation 101.

In some embodiments, the threshold $T1$ is a preconfigured value. In some other embodiments, the threshold $T1$ is 55 determined based on the brightness values Vw and Vb , where Vw is the brightness value when the display unit 12 displays a white image, and Vb is the brightness value when the display unit 12 displays a black image. In some embodiments, the threshold $T1$ equals to:

$$60 \quad C1*(Vw-Vb)+Vb, \text{ in which } C1 \text{ is between } 0 \text{ and } 1.$$

Vw and Vb may be generated during the initialization stage of the display apparatus 1 (or 1a) or during normal operation of the display apparatus 1 (or 1a). In some embodiments, Vw and Vb are fixed values and the threshold 65 $T1$ is preconfigured. Thus, the calculation of the threshold $T1$ can be skipped during the operation of the display apparatus.

FIG. 4 is a flow chart for monitoring a display apparatus according to some embodiments of the present disclosure. The flow chart in FIG. 4 is performed by the controller 15 of display apparatus 1 (or 1a). During operation of the display apparatus 1 (or 1a), the sensing device 14 detects or measures the light and generates the corresponding brightness values. The sensing device 14 may generate brightness values at different time. The brightness values generated by the sensing devices 14 may be expressed as a function associated with time. For example, the brightness values generated by the sensing devices 14 may be expressed as:

$V(t)$, in which t refers to time.

In operation 201, the controller 15 obtains the brightness value $V(t)$ from the sensing device 14. In operation 202, the controller 15 calculates an average brightness value $V_a(t)$ for a past time period. In some embodiments, the average brightness value $V_a(t)$ is an average value of $V(t-n+1)$ to $V(t)$, in which n is a preconfigured integer. In operation 203, the controller 15 determines whether the difference between $V(t)$ and $V_a(t)$ is smaller than a threshold T_2 for a preconfigured time period. In some embodiments, the determination of operation 203 may be expressed as:

$|V(t) - V_a(t)| < T_2$ for every t in the range from (t_2-m+1) to t_2 , in which t_2 denotes the current time and m is an integer which is determined based on the preconfigured time period and the rate of obtaining the brightness values. For example, if the preconfigured time period is 10 seconds and a brightness value is obtained every 2 ms, then m is equal to 5,000.

The difference between $V(t)$ and $V_a(t)$ being smaller than a threshold T_2 for a preconfigured time period means that the displayed content may be still. It may be caused by malfunction of the display unit (e.g., still image) or malfunction of the backlight module. Thus, the controller 15 determines that the display apparatus malfunctions (i.e., operation 204) if the difference between $V(t)$ and $V_a(t)$ is smaller than a threshold T_2 for a preconfigured time period. Otherwise, the controller 15 determines that the display apparatus 1 (or 1a) functions properly and performs operation 201. If the controller 15 determines that the display apparatus 1 (or 1a) malfunctions, the controller 15 may further alarm a remote user through the communication module 16.

In some embodiments, the threshold T_2 is a preconfigured value. In some other embodiments, the threshold T_2 is determined based on the brightness values V_w and V_b , where V_w is the brightness value when the display unit 12 displays a white image, and V_b is the brightness value when the display unit 12 displays a black image. In some embodiments, the threshold T_2 equals to:

$C_2 * (V_w - V_b)$, in which C_2 is between 0 and 1.

In some embodiments, the brightness values V_w and V_b are preconfigured before the operation 201. Thus the threshold T_2 is preconfigured before the operation 201, and the calculation of the threshold T_2 can be skipped during the operation of the display apparatus 1 (or 1a). In some embodiments, V_w and V_b may be generated during the initialization stage of the display apparatus 1 (or 1a) or during normal operation of the display apparatus 1 (or 1a).

FIG. 5A is a flow chart for monitoring a display apparatus according to some embodiments of the present disclosure. The flow chart in FIG. 5A is performed by the controller 15 of display apparatus 1 (or 1a). When the display apparatus 1 (or 1a) is operated (e.g., displaying images or videos), the sensing device 14 detects or measures the light and generates the corresponding brightness values. The sensing device 14 may generate brightness values at different time or different frames. The brightness values generated by the

sensing devices 14 may be expressed as a function associated with time or as a function associated with the ordinal number of frame. For example, the brightness values generated by the sensing devices 14 may be expressed as:

5 $V(t)$, in which t refers to time or the ordinal number of frame.

In operation 301, the controller 15 obtains the brightness value $V(t)$ from the sensing device 14.

When the display apparatus 1 (or 1a) displays images or 10 videos, the display apparatus 1 (or 1a) may turn off the backlight module 13 for short time. In some embodiments, the short time for which the backlight module 13 is turned 15 off may be a portion of one frame. When the display apparatus 1 (or 1a) is operated (e.g., displaying images or videos) without the backlight, the sensing device 14 detects or measures the light and generates the corresponding brightness values. The sensing device 14 may generate brightness values without the backlight at different time or different frames. The brightness values without the backlight 20 generated by the sensing devices 14 may be expressed as a function associated with time or as a function associated with the ordinal number of frame. For example, the brightness values generated by the sensing devices 14 may be expressed as:

25 $V_{nb}(t)$, in which t refers to time or the ordinal number of frame.

In operation 302, the controller 15 obtains the brightness value $V_{nb}(t)$ from the sensing device 14.

FIG. 5B illustrates a frame 511 according to some 30 embodiments of the present disclosure. In FIG. 5B, the frame 511 is divided into two portions 512 and 513. In some embodiments, the backlight module 13 is not turned off in the portion 512, and the backlight module 13 is turned off in the portion 513. In some embodiments, the operation 301 is 35 performed in the portion 512, and the operation 302 is performed in portion 513. In some embodiments, the operation 301 is performed every frame. In some embodiments, the operation 301 is performed every several frames. In some embodiments, the operation 302 is performed every 40 frame. In some embodiments, the operation 302 is performed every several frames. Because the operation 301 may not be performed every frame, if no new brightness value $V(t)$ is obtained, the present brightness value $V(t)$ equals to the recently obtained brightness value $V(t)$. Because the 45 operation 302 may not be performed every frame, if no new brightness value $V_{nb}(t)$ is obtained, the current brightness value $V_{nb}(t)$ equals to the recently obtained brightness value $V_{nb}(t)$.

Referring to FIG. 5A again, in operation 303, the controller 15 obtains the brightness value $V_r(t)$ from the difference 50 between $V(t)$ and $V_{nb}(t)$.

In operation 304, the controller 15 determines whether the 55 difference between $V_r(t)$ and $V_r(t-1)$ (i.e., the value V_r for the current time and the value V_r for the previous time) is smaller than a threshold T_3 for a preconfigured time period, for preconfigured times, or for preconfigured frames. In some embodiments, the determination of operation 303 may be expressed as:

60 $|V_r(t) - V_r(t-1)| < T_3$ for every t in the range from (t_3-m+1) to t_3 , in which t_3 denotes the current time and m is an integer which is determined based on the preconfigured time period and the rate of obtaining the brightness values. For example, if the preconfigured time period is 10 seconds and a brightness value is obtained every 2 ms, then m is equal to 5,000.

65 The difference between $V_r(t)$ and $V_r(t-1)$ being smaller than a threshold T_3 for a preconfigured time period means that the displayed content may be still. It may be caused by

malfunction of the display unit (e.g., still image) or malfunction of the backlight module. Thus, the controller 15 determines that the display apparatus malfunctions (i.e., operation 305) if the difference between $V_r(t)$ and $V_r(t-1)$ is smaller than a threshold T_3 for a preconfigured time period. Otherwise, the controller 15 determines that the display apparatus 1 (or 1a) functions properly and performs operation 301. If the controller 15 determines that the display apparatus malfunctions, the controller 15 may further alarm a remote user through the communication module 16.

In some embodiments, the threshold T_3 is a preconfigured value. In some other embodiments, the threshold T_3 is determined based on the brightness values V_w and V_b , where V_w is the brightness value when the display unit 12 displays a white image, and V_b is the brightness value when the display unit 12 displays a black image. In some embodiments, the threshold T_3 equals to:

$$C_3 * (V_w - V_b), \text{ in which } C_3 \text{ is between 0 and 1.}$$

In some embodiments, the brightness values V_w and V_b are preconfigured before the operation 301. Thus, the threshold T_3 is preconfigured before the operation 301, and the calculation of the threshold T_3 can be skipped during the operation of the display apparatus 1 (or 1a). In some embodiments, V_w and V_b may be generated during the initialization stage of the display apparatus 1 (or 1a) or during normal operation of the display apparatus 1 (or 1a).

FIG. 6 is a flow chart for monitoring a display apparatus 1 (or 1a) according to some embodiments of the present disclosure. The flow chart in FIG. 6 is performed by the controller 15 of display apparatus 1 (or 1a). In some embodiments, the operations shown in FIG. 6 are performed when the display apparatus 1 (or 1a) boots up and may be combined with the operations shown in FIG. 3 4, or 5A. In operation 401, the controller 15 controls the display unit 12 to display a white image. The sensing device 14 detects or measures the light to generate a brightness value V_w when the display unit 12 displays the white image. In operation 402, the controller 15 obtains the brightness value V_w from the sensing device 14. In operation 403, the controller 15 controls the display unit 12 to display a black image. The sensing device 14 detects or measures the light to generate a brightness value V_b when the display unit 12 displays the black image. In operation 404, the controller 15 obtains the brightness value V_b from the sensing device 14. Normally, the brightness value V_w is larger than the brightness value V_b .

In operation 405, the controller 15 determines whether the difference between V_w and V_b is smaller than a threshold T_4 . If the difference between V_w and V_b is not smaller than the threshold T_4 , the controller 15 determines that the environment of the display apparatus 1 (or 1a) is good for detecting the light reflected by the transparent plate 2 or the protective plate 11 (i.e., operation 406). Such environment may be good for the operations shown in FIG. 3 4, or 5A. In some embodiment according to the present disclosure, if the difference between V_w and V_b is smaller than the threshold T_4 , the controller 15 determines that the environment of the display apparatus 1 (or 1a) is not good for detecting the light reflected by the transparent plate 2 or the protective plate 11 (i.e., operation 407). Such environment may be not good for the operations shown in FIG. 3 4, or 5A.

In some embodiment according to the present disclosure, the result of the operation 405 may be used to determine whether the display apparatus 1 (or 1a) functions properly. If the difference between V_w and V_b is not smaller than the threshold T_4 , the controller 15 determines that the display apparatus 1 (or 1a) functions properly (i.e., operation 406).

If the difference between V_w and V_b is smaller than the threshold T_4 , the controller 15 determines that the display apparatus 1 (or 1a) has malfunctioned (i.e., operation 407). For example, if the display unit 12 malfunctions or if the backlight module 13 malfunctions, the displayed image may not change. Thus, the difference between V_w and V_b may be smaller than the threshold T_4 and it can be determined that the display apparatus 1 (or 1a) has malfunctioned. The controller 15 may further alarm a remote user through the communication module 16.

In some embodiments, the threshold T_4 is determined based on values V_{wp} and V_{bp} . The value V_{wp} refers to the brightness value when the display apparatus 1 (or 1a) normally displays a white image. The value V_{bp} refers to the brightness value when the display apparatus 1 (or 1a) normally displays a black image. Values V_{wp} and V_{bp} may be preconfigured values or may be an average of V_w and an average of V_b obtained by the controller 15 at different times. In some embodiments, the threshold T_4 equals to:

$$C_4 * (V_{wp} - V_{bp}), \text{ in which } C_4 \text{ is between 0 and 1.}$$

In some embodiments, the determination in operation 405 can be expressed as:

$$(V_w - V_b) < C_4 * (V_{wp} - V_{bp}).$$

In some embodiments the threshold T_4 is preconfigured, thus the operation calculating the threshold T_4 can be skipped.

As used herein, the singular terms "a," "an," and "the" may include plural referents unless the context clearly indicates otherwise. For example, reference to an electronic device may include multiple electronic devices unless the context clearly indicates otherwise.

As used herein, the terms "connect," "connected," and "connection" refer to an operational coupling or linking. Connected components can be directly or indirectly coupled to one another through, for example, another set of components.

Additionally, amounts, ratios, and other numerical values are sometimes presented herein in a range format. It is to be understood that such range format is used for convenience and brevity and should be understood flexibly to include numerical values explicitly specified as limits of a range, but also to include all individual numerical values or sub-ranges encompassed within that range as if each numerical value and sub-range is explicitly specified.

While the present disclosure has been described and illustrated with reference to specific embodiments thereof, these descriptions and illustrations are not limiting. It should be understood by those skilled in the art that various changes may be made and equivalents may be substituted without departing from the true spirit and scope of the present disclosure as defined by the appended claims. The illustrations may not be necessarily drawn to scale. There may be distinctions between the artistic renditions in the present disclosure and the actual apparatus due to manufacturing processes and tolerances. There may be other embodiments of the present disclosure which are not specifically illustrated. The specification and drawings are to be regarded as illustrative rather than restrictive. Modifications may be made to adapt a particular situation, material, composition of matter, method, or process to the objective, spirit and scope of the present disclosure. All such modifications are intended to be within the scope of the claims appended hereto. While the methods disclosed herein have been described with reference to particular operations performed in a particular order, it will be understood that these operations may be combined, sub-divided, or re-ordered to form an equivalent method without departing from the teachings

of the present disclosure. Accordingly, unless otherwise specifically indicated herein, the order and grouping of the operations are not limitations of the present disclosure.

What is claimed is:

1. A display apparatus, comprising:

a display unit;

a backlight module located on a back side of the display unit;

a light sensor located on a front side of the display unit, the front side being a side that emits light and displays images to a user of the display apparatus, the front side being opposite the back side, and wherein the light sensor faces away from the display unit for detecting and generating a first brightness value of light comprising a combination of ambient light and reflected light, wherein the reflected light is emitted by the backlight module, passes through the display unit and is then reflected back to the light sensor by a transparent plate placed in front of the display apparatus on the front side of the display unit, and wherein the ambient light and the reflected light are simultaneously detected by the light sensor; and

a controller that determines whether the display apparatus is malfunctioning based on the first brightness value, wherein the controller determines the display apparatus is malfunctioning when a difference between the first brightness value and an average value of the first brightness value for a past time period is lower than a second threshold for a time period.

2. The display apparatus of claim 1, wherein the controller determines the display apparatus is malfunctioning when the first brightness value is lower than a first threshold for a time period.

3. The display apparatus of claim 1, wherein the controller further controls the backlight module based on the first brightness value.

4. The display apparatus of claim 1, wherein the light sensor is located on the display unit and outside a display area of the display unit.

5. The display apparatus of claim 1, further comprising a protective plate on the front side of the display unit, and the reflected light is reflected by the protective plate.

6. A display apparatus, comprising:

a display unit;

a backlight module located on a back side of the display unit;

a light sensor located on a front side of the display unit, the front side being a side that emits light and displays images to a user of the display apparatus, the front side being opposite the back side, and wherein the light sensor faces away from the display unit for detecting and generating a first brightness value of light comprising a combination of ambient light and reflected light, wherein the reflected light is emitted by the backlight module, passes through the display unit and is then reflected back to the light sensor by a transparent plate placed in front of the display apparatus on the front side of the display unit, and wherein the ambient light and the reflected light are simultaneously detected by the light sensor; and

a controller that determines whether the display apparatus is malfunctioning based on the first brightness value, wherein the light sensor detects light when the backlight module is turned off and generates a second brightness value; the controller determines a third brightness value for a current time based on a difference between the first brightness value and the second brightness value;

the controller determines that the display apparatus is malfunctioning when a difference between the third brightness value for the current time and the third brightness value for a previous time is lower than a third threshold for a time period.

7. The display apparatus of claim 6, wherein the light sensor detects a fourth brightness value when the display unit displays a white image, and detects a fifth brightness value when the display unit displays a black image, and the third threshold is determined based on the fourth brightness value and the fifth brightness value.

8. The display apparatus of claim 7, wherein the third threshold is equal to a portion of a difference between the fourth brightness value and the fifth brightness value.

9. The display apparatus of claim 7, wherein the controller is further configured to determine an environment of the display apparatus based on a difference between the fourth brightness value and the fifth brightness value and a fourth threshold.

10. The display apparatus of claim 6, wherein the controller determines the display apparatus is malfunctioning when the first brightness value is lower than a first threshold for a time period.

11. The display apparatus of claim 6, wherein the controller further controls the backlight module based on the first brightness value.

12. The display apparatus of claim 6, wherein the light sensor is located on the display unit and outside a display area of the display unit.

13. The display apparatus of claim 6, further comprising a protective plate on the front side of the display unit, and the reflected light is reflected by the protective plate.

14. A method for monitoring a display apparatus having a display unit, a backlight module located on a back side of the display unit, and a light sensor located on a front side of the display unit, the front side being a side that emits lights and displays images to a user of the display apparatus, the front side being opposite the back side, the light sensor facing away from the display unit, the method comprising:

by use of the light sensor, detecting light comprising a combination of ambient light and reflected light, wherein the reflected light is emitted by the backlight module, passes through the display unit and is then reflected back to the light sensor by a transparent plate placed in front of the display apparatus on the front side of the display unit, and wherein the ambient light and the reflected light are simultaneously detected by the light sensor;

generating a first brightness value based on the detected light; and

determining whether the display apparatus is malfunctioning based on the first brightness value.

15. The method of claim 14, further comprising determining that the display apparatus is malfunctioning when the first brightness value is lower than a first threshold for a time period.

16. The method of claim 14, further comprising determining that the display apparatus is malfunctioning when a difference between the first brightness value and an average value of the first brightness value for a past time period is lower than a second threshold for a time period.

17. The method of claim 14, further comprising: generating a second brightness value by detecting light when a backlight module of the display apparatus is turned off;

11

determining a third brightness value for a current time based on the first brightness value and the second brightness value;

determining the display apparatus is malfunctioning when a difference between the third brightness value for the current time and the third brightness value for a previous time is lower than a third threshold for a time period.

18. The method of claim **17**, further comprising: detecting a fourth brightness value when the display apparatus displays a white image; detecting a fifth brightness value when the display apparatus displays a black image; and determining the third threshold based on the fourth brightness value and the fifth brightness value. 10

19. The method of claim **18**, wherein the third threshold is equal to a portion of a difference between the fourth brightness value and the fifth brightness value. 15

20. The method of claim **18**, further comprising determining an environment of the display apparatus based on a difference between the fourth brightness value and the fifth brightness value and a fourth threshold. 20

21. The method of claim **14**, further comprising controlling a backlight of the display apparatus based on the first brightness value.

12
